Primary Examiner — Michael C Stout*Assistant Examiner* — Fitzgerald L Butac(74) *Attorney, Agent, or Firm* — Haynes and Boone, LLP(57) **CLAIM**

The ornamental design for an inspection system, as shown and described.

DESCRIPTION

This U.S. Design Patent Application is related to U.S. Design patent application Ser. No. 29/752,287 filed Sep. 25, 2020 and entitled "Housing," which is incorporated herein by reference in its entirety.

FIG. 1 is a front, left, and top perspective view of the inspection system embodying the new design;

FIG. 2 is a rear, right, and top perspective view thereof;

FIG. 3 is a front, left, and bottom perspective view thereof;

FIG. 4 is a front elevational view thereof;

FIG. 5 is a rear elevational view thereof;

FIG. 6 is a right side elevational view thereof;

FIG. 7 is a left side elevational view thereof;

FIG. 8 is a top plan view thereof; and,

FIG. 9 is a bottom plan view thereof.

The broken lines show portions of an inspection system which form no part of the claimed design.

1 Claim, 9 Drawing Sheets(56)
